RAILWAY TRAFFIC CONTROLLING APPARATUS

Filed May 21, 1924

Patented Mar. 15, 1927.

1,620,691

UNITED STATES PATENT OFFICE.

DANIEL W. RICHARDS AND HARRY P. HANCOCK, OF ROANOKE, VIRGINIA.

RAILWAY-TRAFFIC-CONTROLLING APPARATUS.

Application filed May 21, 1924. Serial No. 714,801.

Our invention relates to railway traffic controlling apparatus, and has for an object the provision of means for enabling a train despatcher or other official to be informed of traffic conditions at a distant point.

In certain respects the present invention is an improvement upon the invention disclosed in an application filed by us in the 10 United States Patent Office on the 25th day of April, 1922, Serial No. 556,506.

We will describe one form of apparatus embodying our invention, and will then point out the novel features thereof in 15 claims.

The accompanying drawing is a diagrammatic view illustrating one form of apparatus embodying our invention.

Referring to the drawing, the reference 20 characters 22 and 22^a designate the track rails of a railway along which traffic normally moves in the direction indicated by the arrow. These rails are divided by insulated joints 23 into a series of track sections of which only one section V—W is shown in the drawing. This section is provided with a track circuit comprising as usual a battery b connected across the rails adjacent one end of the section and a track 25 relay T connected across the rails adjacent the other end of the section. The section V—W is provided with a signal S, which, as here shown, is of the three-position semaphore type arranged to indicate "proceed," "caution" and "stop." This signal is controlled in the usual manner by the track 30 relay T and by other instrumentalities located in advance of the section V—W, but inasmuch as the control of this signal forms 35 no part of our present invention the controlling circuits are omitted from the drawing in order to simplify the disclosure.

The reference character Z designates a 40 train despatcher's office which may be located at a point a considerable distance from the signal S, and which office is connected with the signal location by a transmission line comprising two wires 28 and 29. Located in the despatcher's office Z are two 45 code wheels A and G, arranged to transmit code impulse combinations over the transmission line, and located adjacent the signal S are two Gill selectors B and H well known in the art designed to respond respectively to the code impulse combinations 50 transmitted by the wheels A and G. Lo-

cated adjacent the signal and controlled thereby is a code impulse wheel 6 arranged to transmit an impulse combination over the transmission line 28, 29 to the despatcher's 60 office Z where it gives the despatcher an audible code clicking indication in his telephone N bridged across the line wires 28, 29. A different code impulse combination is used for each signal, and the code wheel 6 is 65 arranged to repeat the impulse combination several times when it is released by the movement of the signal to stop position.

In order to illustrate the operation of the apparatus we will first assume that the 70 despatcher desires to be informed as to the indication given by signal S. The procedure for accomplishing this is as follows: The despatcher first operates code wheel A, thereby causing operation of a telegraph 75 relay 24, through a circuit which includes a battery 25 and the contact 26 of wheel A. The operation of relay 24 causes the transmission of an impulse combination from the despatcher's office to the selectors H and 80 B, over a circuit which will be obvious from the drawing, and which includes a battery 27. Selector B responds to the particular impulse combination transmitted by wheel A, so that contact 2 of this selector becomes 85 closed. When contact 2 closes it energizes a repeating relay C' by means of a circuit which passes from terminal B' of a battery 11, through contact 2, right hand winding 42 of selector B, wire 10, and winding of 90 relay C' to terminal O' of the battery 11. Battery 11 may advantageously be a battery having a potential of about 10 volts. When contact 2 of selector B becomes 95 closed, it remains closed until the operating winding 35 becomes energized by another impulse combination transmitted over the line 28, 29, or until a single impulse is transmitted over the line by suitable means, such as a key R in the despatcher's office, which 100 when closed causes relay 24 to close. The other selector H hereinafter referred to has the same characteristics as selector B. The auxiliary windings 42 and 95 on these selectors are the usual "answer-back" windings 105 of the Gill selector, and they perform no function in the system disclosed in the present application.

Relay C' when closed, closes the pick-up 110 circuits for two stick relays C² and D'. The pick-up circuit for relay C² is from terminal B' of battery 11, through contact

13, wire 14, winding of relay C², and wire 15 to terminal O' of battery 11. The stick circuit for relay C² is not closed unless track relay T is de-energized, which condition will be considered hereinafter; that is to say, for the present we will assume that track relay T is energized. The pick-up circuit for relay D' is from terminal B', through contact 18 of relay C', wire 19, winding of relay D' to terminal O'.

10 Relay D' is provided with two stick circuits, one of which passes from terminal B' through wire 45, back contact 46 of a relay J, wires 47 and 40, contact C⁴, wire 32, contact 33 of relay D', wire 34, and winding of relay D' to terminal O'. Contact C⁴ is normally closed, and is momentarily opened by a pin 6^a on code wheel 6 just before this wheel completes its operation but after the completion of the code impulse combinations transmitted by this wheel. The movement of signal S from the proceed to the stop position requires less time than the full revolution of wheel 6 when released by such signal operation, and so it will be clear that relay D', when closed, will remain closed until after signal S reaches the stop position and the code wheel 6 has completed its impulse combinations.

15 The second stick circuit for relay D' passes from terminal B' through contact 3 operated by signal S, wires 23 and 31, contact C⁴, wire 32, contact 33, wire 34, and winding of relay D' to terminal O. Contact 3 is closed when signal S indicates proceed or caution, but is open when the signal indicates stop. This second stick circuit keeps relay D' closed until signal S moves below the caution position, even though the first stick circuit may be opened at contact 46 of relay J, and so, as hereinafter explained, after the despatcher has conditioned the apparatus to receive an indication of movement of signal S to the stop position he cannot cancel this condition until the signal actually moves to the stop position.

20 While relay C² is closed it closes a pick-up circuit for a relay D², which circuit passes from terminal B' through contact 7 operated by signal S, wire 36, contact 37 of relay C², wire 39, winding of relay D² to terminal O'. Contact 7 is closed only while signal S indicates proceed or caution, and so the pick-up circuit of relay D² is closed only when the signal is in one or the other of these positions. Relay D² is provided with two stick circuits, one of which passes from terminal B', through contact 3, wires 23, 40 and 41, contact 43, wire 44, and winding of relay D² to terminal O'. This stick circuit will open as soon as signal S moves below the caution position. The other stick circuit for relay D² is from terminal B', through wire 45, back contact 46 of relay

J, wires 47 and 41, contact 43 of relay D², wire 44, and winding of relay D² to terminal O'. This stick circuit will of course, remain closed until relay J becomes energized.

25 Indications concerning the traffic conditions in section V-W are transmitted to the despatcher's office Z through the medium of a transformer Q, the secondary of which is connected directly across wires 30 and 38, and which wires in turn are connected across the transmission wires 28, 29.

30 Assuming that signal S is in the proceed position, track relay T is energized and relays C², D² and D' are closed, the circuit for the primary of transformer Q is from terminal B² of a battery 12, through primary 53, wires 54 and 55, contact 56 of relay C², wire 57, contact 58 of relay D², wire 59, contact 5^a-5, wire 60, contact 61 of relay T, wires 62 and 63, and a vibrating device E to terminal O² of battery 12. The vibrating device E in the form here shown is an electric bell, and the battery 12 may conveniently have a potential of about 3 volts. While the circuit just traced is closed, the pulsations due to the operation of the bell E are impressed on the transmission line and may be heard by the despatcher as a buzz in his telephone N. If these pulsations are heard, they inform the despatcher that signal S is in the proceed position and that the apparatus is properly set up to give a distinctive indication when the signal moves to the stop position. The buzz in the despatcher's telephone will continue as long as relay C² remains closed, but this relay may be opened by releasing contact 2 of selector B, and this may be accomplished by the despatcher's telegraph key R or it will be accomplished if any code impulse combination is impressed on the transmission line 28, 29.

35 The battery 12 has relatively low voltage, and the primary 53 of transformer Q preferably has relatively few turns, so that the energy applied to the line wires 30 and 38 by transformer Q is not sufficient to actuate the selector armature and so to release contact 2.

40 We will now assume that with relays D', D² and C² closed, a train enters section V-W, thereby opening track relay T and causing signal S to move to the stop position. This movement of signal S releases the code wheel 6 which then operates to impress a series of code impulse combinations on the primary of transformer Q through the following circuit: from terminal B², through primary 53, wires 54 and 64, back contact 65 of track relay T, wire 66, contact 67 of relay D', wire 68, code wheel contact 169, and wire 69 to terminal O². This series of impulse combination is of course impressed on the transmission wires 28, 29 by transformer Q and

so may be heard in the despatcher's telephone N, informing him that signal S has moved to the stop position.

After signal S passes the caution position, 5 the second stick circuit for relay D' opens at contact 3, but the first stick circuit for this relay remains closed until after the signal has reached the stop position and the operation of code wheel 6 is almost completed, where- 10 upon contact 6 is opened by pin 6^a. Relay D' then opens. One of the stick circuits for relay D² is also opened at contact 3, but the other stick circuit for this relay remains closed at back contact 46 of relay J, so that 15 relay D² remains closed. As soon as signal S reaches the stop position, a second buzzer circuit is closed, which circuit passes from terminal B², through primary 53 of transformer Q, wires 54 and 70, back contact 71 20 of relay J, wire 72, contact 73 of relay D², wires 74 and 75, contact 5^b—5, wires 60 and 76, back contact 77 of relay D', wires 78 and 63, and bell E to terminal O². This causes 25 a buzz in the despatcher's telephone which will persist as long as the train occupies any 30 part of section V—W, but the buzz may be discontinued by the despatcher in the following manner: Code wheel G is operated to send a distinctive impulse combination over the transmission line, which combination is such as to cause selector H to respond. This selector then closes a circuit which passes from terminal B', through winding 95 35 of selector H, contact 9 of selector H, wires 48 and 49, and winding of relay J to terminal O'. This causes relay J to close, there- 40 upon opening at back contact 46 the second circuit for relay D², whereupon the latter relay opens, with the result that the buzzer circuit last traced becomes opened at contacts 71 and 73. In order to prevent relay J from being held closed, the wheel G is 45 preferably provided with an extra tooth which insures the release of selector H as soon as the function of this selector has been accomplished.

One important feature of our apparatus is that when signal S is at caution or proceed 50 and the despatcher has caused relay D' to become closed so that a code impulse indication will be transmitted when the signal goes to stop, the despatcher cannot release relay D' and so cancel the condition by closing relay J, because relay D' will remain closed 55 due to its second stick circuit through contact 3 until the signal goes to stop.

Assuming that the despatcher does not 60 operate selector H to release relay D², this relay will automatically become released when the train passes out of section V—W. As soon as relay T becomes energized and before the signal S moves away from the stop position, relay J becomes energized by 65 a circuit which passes from terminal B', through front contact 50 of track relay T,

wire 51, contact 4, wires 52 and 49, and winding of relay J to terminal O'. The closing of relay J will release relay D², and as soon as signal S moves away from the stop position the circuit for relay J will be 70 opened at circuit controller 4. The parts of the apparatus are then restored to their initial condition.

We will now assume that when the despatcher operates code wheel A, the section 75 V—W is occupied by a train, so that track relay T is open and signal S is at stop. Relays C', C² and D' will all be closed as before, due to the closing of contact 2 in selector B. The relay D² will not close, how- 80 ever, because its pick-up circuit is opened at contact 7. All circuits for bell E will then be opened, so that there will be no buzz in the despatcher's telephone. In order to determine whether or not the absence of a buzz 85 means that the track section is occupied, the despatcher then operates code wheel G, thereby closing contact 9 of selector H, which in turn causes relay J to be closed. The signal thus sent over the transmission 90 line releases contact 2 of selector B, so that relays C' and D' will open, but relay C² will remain closed because its stick circuit is closed through back contact 50 of track relay T and contact 21 of relay C². A buzzer 95 circuit is then closed which passes from terminal B², through primary 53, wires 54 and 70, front contact 71 of relay J, wire 79, contact 80 of relay C², wires 81 and 75, contact 5^b—5, and wires 60 and 76, back contact 100 77 of relay D', wires 78 and 63, and bell E to terminal O². Relay J will open at once due to the extra tooth on code wheel G, but during the time that this relay is closed the despatcher will receive a buzz in his telephone N which will indicate to him that section V—W is occupied. As soon as the 105 train passes out of this section, track relay T will close, thereby releasing relay C².

One important feature of our invention 110 is the fact that it requires no equipment in the despatcher's office other than that usually provided, except the additional code wheels which control the selectors located at the wayside signals. The usual telephone apparatus in the despatcher's office is employed for indications of traffic conditions.

Another important feature of our invention 115 is the fact that all indications received by the despatcher are audible, the meaning of each indication being determined by its nature and by the condition of the apparatus in the despatcher's office. Thus when a condition has been properly set up at a given signal whereby the next train moving in the proper direction will transmit an indication, this fact is announced to the despatcher by a buzz in his telephone receiver. When such train passes the signal, the fact 120 is indicated to the despatcher by a clicking 125 130

due to the impulse combination of the code wheel at such signal, which clicking continues as long as the signal is moving to the stop position. This clicking indication is 5 followed by a buzzing indication which continues until the despatcher operates his code wheel G thereby actuating selector H. Should the despatcher fail to operate code wheel G, or should the selector H fail to 10 respond to operation of wheel G, the buzzing indication is automatically discontinued when the train passes out of the immediate track section and the indication transmitting apparatus at the signal is automatically disconnected 15 from the despatcher's office so that the next train in the same direction will give no indication unless the despatcher has again operated his code wheel A. If the despatcher receives no indication in response 20 to operation of code wheel A, but does receive a buzz in response to subsequent operation of code wheel G, he knows that the track section is occupied. This buzz is automatically discontinued due to the extra tooth on code wheel G.

Although we have herein shown and described only one form of apparatus embodying our invention, it is understood that various changes and modifications may be made 30 therein within the scope of the appended claims without departing from the spirit and scope of our invention.

Having thus described our invention, what we claim is:

35 1. In combination, a section of railway track provided with a track circuit including a normally closed track relay, a signal for said section controlled by said track relay, a transmission line extending from said signal to a distant point, a transformer the secondary of which is connected across said transmission line, a code impulse transmitting mechanism controlled by said signal, a circuit for said mechanism including a 40 source of current and a back contact of said track relay and the primary of said transformer, and means located at said distant point for receiving the impulse combination transmitted by said mechanism.

50 2. In combination, a section of railway track provided with a track circuit including a normally closed track relay, a signal for said section controlled by said track relay, a code wheel operated by said signal, a local circuit for said code wheel including a source of current and a back contact of said track relay, and means located at a distant point for receiving the impulse combination transmitted by said code wheel.

55 3. In combination, a section of railway track provided with a track circuit including a normally closed track relay, a signal for said section controlled by said track relay, a stick relay associated with said signal, means including a selector at the

signal and a code wheel at a distant point for closing said stick relay, means for subsequently keeping said stick relay closed until said signal changes to the stop indication, a second code wheel operated by said signal, 70 a local circuit for said second code wheel including a source of current and a front contact of said stick relay and a back contact of said track relay, and means located at said distant point for receiving the impulse combination transmitted by said second code wheel.

4. In combination, a section of railway track provided with a track circuit including a normally closed track relay, a signal for said section controlled by said track relay, a stick relay associated with said signal, means including a selector at the signal and a code wheel at a distant point for closing said stick relay, means for subsequently keeping said stick relay closed until said signal changes to the stop indication, receiving means located at said distant point, and means operating when said signal changes to the stop indication for transmitting a distinctive indication to said receiving means provided that said stick relay is closed and said track relay is open.

5. In combination, a railway signal, a stick relay associated therewith, means including a selector at the signal and a code wheel at a distant point for closing said relay, a first stick circuit for said relay closed until said signal changes to the stop indication, an auxiliary relay, a second stick circuit for said stick relay including a back contact of said auxiliary relay, indication transmitting means controlled by said signal and effective only when said stick relay is closed, and means including a second selector 95 at the signal and a second code wheel at said distant point for energizing said auxiliary relay and thereby opening said stick relay if said signal is at stop.

6. In combination, a railway signal, a stick relay associated therewith, means including a selector at the signal and a code wheel at a distant point for closing said relay, a first stick circuit for said relay closed until said signal changes to the stop indication, an auxiliary relay, a second stick circuit for said stick relay including a back contact of said auxiliary relay, indication transmitting means controlled by said signal and effective only when said stick relay is closed, means 110 including a second selector at the signal and a second code wheel at said distant point for energizing said auxiliary relay and thereby opening said stick relay if said signal is at stop, a track circuit including a track relay for controlling said signal, and other means for energizing said auxiliary relay when said signal is at stop and said track relay is closed.

7. In combination, a railway signal, a 130

- stick relay associated therewith, means including a selector at the signal and a code wheel at a distant point for closing said relay, a first stick circuit for said relay closed 5 until said signal changes to the stop indication, an auxiliary relay, a second stick circuit for said stick relay including a back contact of said auxiliary relay, a vibrating device adjacent said signal, means for operating 10 said device while said signal is at stop and said stick relay is closed, means for detecting operation of said device at said distant point, and means including a second selector at the signal and a second 15 code wheel at said distant point for energizing said auxiliary relay and thereby opening said stick relay if said signal is at stop.
8. In combination, a railway signal, a stick relay associated therewith, means including a selector at the signal and a code wheel at a distant point for closing said relay, a first stick circuit for said relay closed until said signal changes to the stop 20 indication, an auxiliary relay, a second stick circuit for said stick relay including a back contact of said auxiliary relay, a vibrating device adjacent said signal, means for operating said device while said signal is at stop and said stick relay is closed, means for detecting 25 operation of said device at said distant point, and means including a second selector at the signal and a second code wheel at said distant point for energizing said auxiliary relay and thereby opening said stick relay if said signal is at stop, a track circuit including a track relay for controlling said signal, and other means for energizing said auxiliary relay when said signal is at stop and said track relay is closed.
- 40 9. In combination, a railway traffic controlling device, a transmission line extending from said device to a distant point, a relay associated with said device, means including a code wheel at said distant point and a selector located at said signal and both connected with said line for closing said relay, means for subsequently keeping said relay closed while said signal indicates proceed, a transformer the secondary of which is
- connected across said transmission line, a 50 vibrating device, a circuit for said vibrating device controlled by said relay and by said traffic controlling device and including the primary of said transformer, and means connected with said transmission line at said 55 distant point for detecting operation of said vibrating device.
10. In combination, a railway signal, a track circuit including a track relay for controlling said signal, two stick relays associated with said signal, means including a selector at said signal and a code wheel at a distant point for closing both of said 60 relays, means for subsequently keeping the first relay closed until said signal changes to the stop indication, means for subsequently keeping the second relay closed until said signal indicates stop and said track relay is energized, code impulse transmitting means controlled by said signal and said 65 first relay, and other indication transmitting means controlled by said signal and by said second relay.
11. In combination, a railway signal, a track circuit including a track relay for controlling said signal, two stick relays associated with said signal, means including a selector at said signal and a code wheel at a distant point for closing both of said 70 relays, means for subsequently keeping the first relay closed until said signal changes to the stop indication, means for subsequently keeping the second relay closed until said signal indicates stop and said track relay is energized, means including a second 75 selector at the signal and a second code wheel at said distant point for opening said second relay after said signal changes to the stop indication and before said track relay becomes energized, code impulse transmitting 80 means controlled by said signal and said first relay, and other indication transmitting means controlled by said signal and by said second relay.

In testimony whereof we affix our signatures.

DANIEL W. RICHARDS.
HARRY P. HANCOCK.
